UNITED STATES PATENT OFFICE.

JOHN R. LONG, OF EAST AKRON, OHIO.

PIPE-CUTTER.

1,019,063.

Specification of Letters Patent.

Patented Mar. 5, 1912.

Application filed July 28, 1911. Serial No. 641,134.

To all whom it may concern:

Be it known that I, JOHN R. LONG, citizen of the United States, residing at East Akron, in the county of Summit and State 5 of Ohio, have invented certain new and useful Improvements in Pipe-Cutters, of which the following is a specification.

My invention relates to improvements in pipe cutters, and particularly upon the style 10 of cutter originally shown and set forth in my application for Letters Patent of the United States, Ser. No. 613,608, all substantially as shown and described and particularly pointed out in the claim.

15 In the accompanying drawings, Figure 1 is a sectional elevation of the invention lengthwise axially, and Fig. 2 is a plan view of the thereof. Fig. 3 is a perspective view of the inner cutter jaw, and Fig. 4 is a cross section 20 substantially on line $x-x$, Fig. 1. Fig. 5 is a perspective of the inner jawholder or support.

In the construction above referred to and 25 upon which this invention is an improvement the inner jaw support or holder 2 was recessed in its bottom and front so as to provide room beneath and within the same for the inner jaw 3, which rested directly 30 upon the tapered shank of the outer jaw member 4, and the sleeve or yoke 5 was the same as shown herein, flaring slightly in the direction of said jaws and adapted to lock the parts 2 and 4 together in working relation as is now well known in several 35 wrenches patented by me. Likewise the screw 6 was engaged through a lengthwise threaded bore in the rear inner portion of holder 2 and was rotarily confined in a socket in the heel of jaw 3 as shown herein, 40 the said jaw meanwhile having its support directly upon the shank of the lower jaw and its rotary cutter c at its top and front of the holder 2 as also in this case.

The difficulty as to the original construction 45 thus generally described was that the jaw member 3 lay directly between the holder 2 and the shank 4, and that when the yoke was moved forward upon the parts to working position and the cutter was put at 50 work the slack both above and below the member 3 not only had to be taken up but there was a tendency to tilt down and bind at the front of said parts with the effect that the said jaw 3 would become locked and

could not be operated by screw 6. Now, by 55 my construction, I have effectually overcome and remedied this objection by providing the supporting member 2 with a lengthwise cavity or recess 7 which is oblong in cross section with flat sides and of the same proportions its full depth to receive the shank or body of the jaw member 3. It will be noticed that the said jaw member projects about two-thirds its length into said cavity and that the bottom wall 8 of said cavity is 60 part of the jawholder and is flat on its outside and lies directly upon the flat edge of outer jaw member 4. It follows that the said jaw 3 is not in anywise affected by the action of the yoke upon the parts 2 and 4, 65 and that it is equally free to slide back and forth at all times regardless of whether the yoke is locked or loose. This makes the said jaw 3 responsive to the adjusting screw 6 by which it is advanced as the cutting of the 70 pipe progresses and while parts 2 and 4 are firmly and fixedly yoked together. The front end of jaw 4 is curved upward and carries two cutters c' and c'' at different elevations and so as to come respectively above 75 and below the advancing cutter c .

It is also to be observed that in the present construction the respective outer edges of the main jaw and the slidable jawholder are rounded in cross section, as is also the yoke 80 to match, as clearly seen in Fig. 4, and which is material in contributing to the overcoming of the tendency of the flat or angular edges heretofore used to become bound and locked together. As to this it should be understood that there is a disposition in the construction to wedge so tightly within the yoke that often it is difficult to separate the parts, and the present rounded formation 85 is therefore material and of the essence of the present invention because it practically eliminates this objection while it is none the less quick and effective in producing the temporary locking required.

A detaining screw 9 engages through yoke 100 5 into a slot or recess 10 in the side of the slidable member 2.

The threaded bore for screw 6 in jawholder 2 is coincident with the recess 7, axially. It will also be seen that the two 105 jaw supporting members 2 and 4 are reversely tapered, the main member being tapered to a smaller size next to its own jaw

12 carrying the cutters c' and c^2 and the
slidable member 2 being tapered reversely or
rearwardly.

What I claim is:

- 5 A pipe cutter having fixed and movable
jaws respectively provided each with a ro-
tary cutter and a slidable holder for the in-
ner of said jaws having a recess lengthwise
in its bottom open from the front and in
- 10 which said inner jaw is adjustable, the said
fixed jaw and the said slidable holder being
tapered in opposite directions along their

outer edges, a yoke confining said parts in
operative relations and a handle threaded
lengthwise through the lower portion of said 15
slidable holder and rotatably locked in the
said slidable jaw.

In testimony whereof I affix my signature
in presence of two witnesses.

JOHN R. LONG.
